(57) **CLAIM**

The ornamental design for a control box for a compressor, as shown and described.

DESCRIPTION

FIG. 1 is a perspective view as seen from the top and rear of a control box or similar article thereof.

FIG. 2 is a perspective view as seen from the right hand side of the control box.

FIG. 3 is a rear view of the control box.

FIG. 4 is a front plan view of the control box; and,

FIG. 5 is a perspective view as seen from the bottom and rear of the control box.

The left hand side view is not shown and therefore not claimed as part of the invention.
